AUXILIARY TABLE TOP

Edward A. Sherman, Washington, D. C.

Application March 21, 1947, Serial No. 736,327

2 Claims. (Cl. 311—106)

1

This invention relates to table top enlargements and more particularly to that type whereby a supplemental table top, larger than the original, may be secured to the original top.

One object of this invention is to provide an enlarged and supplemental table top designed to be readily secured to and equally readily detached from a smaller table top.

Another object of this invention is to provide an enlarged table top, made of two independent sections, designed to be readily secured to and equally readily detached from the top of a conventional extensible table.

A still further object of this invention resides in a means for securing the enlarged top or its sections to the original and smaller table top whereby the surface finish of the latter will not in any way be marred by the securing means or the supplemental top itself.

Other objects and advantages of this invention will be readily comprehended from the following description of this device given in conjunction with the accompanying drawings wherein

Figure 1 is a top view of the supplemental table top attached to the original and smaller table top with a central cut-away portion revealing the securing means of the supplemental table top.

Figure 2 is a cross sectional view of the supplemental table top attached to the original and smaller table top along the line 2—2 of Fig. 1.

Figure 3 is an enlarged partial view, similar to that shown in Fig. 2, showing in detail the means for securing the supplemental top to the original table and showing the two halves of the top still slightly separated.

Figure 4 is a fragmentary perspective.

Similar reference numbers refer to similar parts throughout the several drawings.

The original and smaller table top, upon which the supplemental top may be secured, is of the conventional type of extensible table wherein its two sections may be separated so as to insert, according to the usual method employed at present, a board or table top section for enlarging the top. However, according to the present invention, instead of inserting an enlarging section in the opening between the two table halves, an entirely new and larger top is placed upon the table and secured thereto by employment of this transverse slidability existing between the two halves of the original table top.

The supplemental table top of this invention consists of two separate and independent halves intended, when properly mounted upon a conventional extensible table, to come together along

2

edges 27, this engagement being located along a middle line of the original table, to form a complete and new table top covering the entire top of the original table and extending beyond its original limits to form an enlarged top for said table as shown in Fig. 1, reference characters 21 and 30 designating the two independent halves.

These halves, 21 and 30, of the supplemental table top are substantially identical in every respect except along engaging edges 27, where one half, 21, has dowel pins 23 protruding therefrom at suitable intervals, while the corresponding edge of the other half, 30, has dowel pin sockets 31 therein, properly arranged to receive dowel pins 23 when these two edges are brought into engagement.

The two supplemental table top halves are in every other respect identical, each consisting of: a flat table top portion 22, shown as a half oval in Fig. 1 as one suitable design; a depending decorative skirt 27; a suitable pad on the under surface of portion 22 to prevent its marring the finish of the original table top upon which it rests, shown in Figs. 1, 2, and 3 in one possible form of several relatively small pads 26 made preferably of felt or other suitable material; and cleat 20 depending along the engaging edge, centrally located there along, but need not be coextensive therewith.

Cleat 20, having clamping or gripping springs 25 attached to it, and having slot 24 substantially coextensive with itself, affords the means whereby the supplemental table top is attached to the original table. Springs 25 extend beyond the edge of section 20 in the direction away from engaging edge 27 such that when the table top half is affixed to the original top 11, these springs will pass under and clamp upon it as shown in Fig. 3. In addition, to avoid interference from dowel pins 14, which may be present in the original table top, when section 20 is brought into contact with edge 41 of table top 11, slot 24 is formed in this section to receive those pins.

Thus, in the attachment of the supplemental top, the two halves of the original table are pulled apart. Each supplemental table top half is then placed upon each half of the original table top such that portions 20 will lie in the opening between the two original table halves as created by their separation, table top portions 22 resting on portions 11 of the original table, pads 26 being interposed between these two surfaces. These supplemental table top halves are then positioned so that sections or cleats 20 abut table top halves 11 along edges 41, while clamping springs 25 en-

gage their undersides. Slots 24, extending substantially along the length of sections 20, avoid interference with possible dowel pins 14 of the original table.

A partial cross sectional view of the union of each supplemental table top half joined to its respective table half is shown in Fig. 3.

After having secured the two supplemental table top halves to the original table top, the two halves of the table are pushed together until edges 27 of the two supplemental halves come together, dowel pins 23 of half 21 entering their respective sockets 31 of supplemental half 30. Fig. 2 shows a cross section of the table supplied with the supplemental table top in its final assembled state.

The removal of the supplemental table top is accomplished by reversing, step by step, the above described process for securing it to the original table.

Although shown in the drawings of this disclosure as a substantially oval supplemental table top attached to an essentially rectangular original top, it is apparent that either the original or the supplemental top may be made in any desired shape. It is also obvious that this invention is applicable to a great variety of sizes, the only limitation being that the overhang of the supplemental top beyond the original top is inherently limited by the loss of stability when the edge of a table extends too far beyond its supporting legs.

Although the embodiment of this invention as specifically described in this specification has been directed to its application for the enlargement of the top of the conventional type of extensible table, several modifications within the scope of this invention are obvious. For example, each of the two supplemental table top halves may be applied to independent small tables, such as bridge tables or end tables, and secured thereto by application of the cleat and clamping springs to one edge of the table in a similar manner as that described above. The two tables with their supplemental tops may then be brought together and positioned so that the dowel pins of one half will enter the dowel pin sockets of the other to form a single large table top. Still further, the supplemental top may be designed to be of only one section for the purpose of enlarging smaller tables such as bridge or end tables or for applying a more decorative top thereto. For said purpose, the cleat 20 is placed inwardly of the edge of the supplemental top so that it will, when attached to a small table, rest uniformly thereon while the depending skirt 27 is extended to all edges of the top affording it symmetry.

The structure of the supplemental tops 30 together with the cleats 20 and the resilient gripping elements 25 are duplicates of each other.

As a result each half may be placed over either end or either half of the original table.

I claim:

1. In combination, an extensible table and a removable enlarged table top therefor, said removable top consisting of two substantially duplicate halves, each comprising a main body portion constituting the enlarged table top and an elongated rigid anchoring strip integral along its length with the underside of said body portion and adjacent one edge thereof, said strips entering between and abutting the separable edges of said extensible table top, resilient gripping means carried by the underside of the anchoring strip for engaging the lower face of the extensible table top and for holding the removable table top in temporary but firm assembly therewith, each of said anchoring strips having a groove substantially coextensive with it for receiving dowel pins projecting from said extensible table, and one of said removable top halves having dowel pins extending from the edge adjacent said strip, the other half having suitable sockets for receiving said pins along its corresponding edge.
2. An enlarged table top for temporary attachment to a smaller extensible table top, consisting of two substantially duplicate halves, each comprising a main body constituting the enlarged top and an elongated rigid anchoring strip integral along its length with the underside of said main body adjacent one edge thereof for entering the opening between the halves of the extensible table top and abutting the separable edges of said extensible table top, resilient gripping means carried by the underside of the anchoring strip for engaging the lower face of the extensible table top and for holding the removable table top in temporary but firm assembly therewith, each of said strips having a groove substantially coextensive with it for receiving dowel pins projecting from said extensible table, and one of said removable top halves having dowel pins extending from the edge adjacent said anchoring strip, the other half having suitable sockets for receiving said pins along its corresponding edge.

EDWARD A. SHERMAN.
